UNITED STATES PATENT OFFICE.

JOSEPH M. WORTHINGTON, OF ANNAPOLIS, MARYLAND.

DESIGN FOR A FRAME FOR PRESCRIPTION-CABINETS.

SPECIFICATION forming part of Design No. 28,032, dated December 14, 1897.

Application filed October 2, 1897. Serial No. 653,862. Term of patent 14 years.

To all whom it may concern:

Be it known that I, JOSEPH M. WORTHINGTON, a citizen of the United States, residing at Annapolis, in the county of Anne Arundel and State of Maryland, have invented and produced a new and original Design for a Frame for Prescription-Cabinets, of which the following is a specification, reference being had to the accompanying drawing, forming part thereof, in which the figure is a perspective view showing my new design.

As shown in the drawing, the leading or material feature of my design consists of the flat intermediate table portion A and the

frames B and C, ranging above and below said portion A at the opposite ends thereof. The portion A is supported from a base F' by end posts and by a central cupboard-like representation F². The frames B include corner-posts and cover-plates B'.

What I claim is—

The design for the frame of a prescription-cabinet as herein shown and described.

JOSEPH M. WORTHINGTON.
